UNITED STATES PATENT OFFICE.

JOHN B. CLEAVELAND, OF INDIANAPOLIS, INDIANA.

DESIGN FOR A FENCE-GATE.

SPECIFICATION forming part of Design No. 19,769, dated April 22, 1890.

Application filed February 14, 1890. Serial No. 340,479. Term of patent 7 years.

To all whom it may concern:

Be it known that I, JOHN B. CLEAVELAND, a citizen of the United States, residing at Indianapolis, in the county of Marion and State of Indiana, have invented and produced a new and original Design for Fence-Gates, of which the following is a specification, reference being had to the accompanying drawing, forming part thereof.

10 The figure is a front elevation of a fence-gate showing my design.

The leading features of my design are a rectangular outline *a*, having a central diametrical straight bar *b*, a pair of angles *c c*, arranged on opposite sides of the straight bar, so as to form therewith a pair of opposed triangles, circles *d d*, arranged in said triangles, each circle being of the largest diameter which can be described in the triangle, a straight

bar *e*, extending diametrically across each circle, and reversed scrolls *ff*, arranged in the circles on opposite sides of the cross-bar. Reversed scrolls *g*, arranged in the corners of the rectangle, may be added.

What I claim as my invention is

25 The design for a fence-gate herein shown and described, the same comprising the rectangular outline *a*, the central straight bar *b*, triangles *c c*, arranged on opposite sides of the central bar, circles *d d* described within 30 the triangles, each circle inclosing a straight bar *e*, and a pair of reversed scrolls *ff*, all combined in the manner set forth.

JOHN B. CLEAVELAND.
